WRITING INSTRUMENT

John C. Wahl, Chicago, Ill., assignor to Ever-sharp, Inc., Chicago, Ill., a corporation of Delaware

Application December 21, 1945, Serial No. 636,406

3 Claims. (Cl. 120—42.03)

1

The present invention has to do with writing instruments of the type in which a thick ink is transferred to the paper or other surface by a small ball which is rotatably mounted in the tip of the instrument.

The object of the invention is to provide, in a writing instrument of the character described, improved means for insuring a satisfactory feed of the ink to the writing ball.

This is accomplished, according to the present invention, by retaining the supply of ink for the instrument in a reservoir and applying pressure to the ink by means of a small air pumping device associated with the reservoir.

Other more specific objects and advantages of the invention will be apparent to those skilled in the art upon a full understanding of the construction and manner of operation of the new ink feeding means.

Three embodiments of the invention are presented herein by way of exemplification, but it will of course be appreciated that the invention is susceptible of incorporation in other structurally modified forms coming equally within the scope of the appended claims.

In the accompanying drawings:

Fig. 1 is an enlarged longitudinal section through a writing instrument equipped with the new ink feeding means;

Fig. 2 is a similar section, with the parts of the instrument in partially disassembled relation;

Fig. 3 is a transverse section, taken on the line 3—3 of Fig. 1;

Fig. 4 is an enlarged longitudinal section through another writing instrument, showing a somewhat different embodiment of the invention; and

Fig. 5 is an enlarged longitudinal section of another writing instrument of the capless projectable tip type, showing another embodiment of the invention.

The writing instrument shown in Figs. 1, 2 and 3 includes an elongated casing 10 which contains a cylindrical chamber 11. The front end of the casing 10 tapers forwardly and is provided with a relatively short axial bore 12. The rear end of the casing 10 is closed by a screw threaded cap 13, which can be readily removed.

An ink reservoir 14 is positioned in the chamber 11 of the casing. This reservoir includes an elongated outer tube 15, an elongated inner sack 16 in which the reserve supply of ink is held, and a nipple 17 to which the front ends of the tube 15 and sack 16 are secured. The nipple 17 is reduced abruptly in diameter at the front end of the tube 15, and the reduced portion 18 of the nipple projects forwardly through the bore 12 in the front end of the casing.

The nipple 17 contains a small axial bore 19 which is progressively reduced in diameter from

2

its rear to its front end and terminated in a minute duct 20 which opens into a socket 21. A small ball 22—on the order of 1 mm. in diameter—is rotatably mounted in the socket 21 and serves to transfer the ink from the duct 20 to the paper or other material. The ink used is preferably a thick viscous ink, as distinguished from an ordinary fountain pen ink.

The reservoir 14 is fixedly but removably secured within the chamber 11 of the casing 10 by means of a forwardly tapering collet 23, which collet is interiorly threaded at 24 and is screwed onto an exteriorly threaded section 25 of the forwardly projecting portion 18 of the nipple 17. The collet 23 abuts against the front end 26 of the casing 10 and, upon being screwed up tightly against the end 26, serves to draw the front end 27 of the reservoir into tightly clamped engagement with the front end 28 of the chamber 11.

The rear end 29 of the tube 15 is sleeved over and fixedly secured to a valve plug 30, which plug contains an axial air passage 31. The passage 31 is normally closed at its front end by a small check ball 32 which is located within a recess in the plug 30. The ball 32 is seated by a spring 33 which is retained in position by an apertured screw plug 34. A collar 35 is screwed over the rear end of the plug 30, in rearwardly projecting relation to the latter, and is provided intermediate its ends with a small laterally directed air inlet 36.

A forwardly opening cup 37 is mounted in the rear end of the collar 35, in freely slidable but substantially air-tight association with the same, and is limited in its rearward movement by an inturned rim 38 on the rear end of the collar 35. In the rearmost position of the cup 37 the inturned rim 38 engages with a small annular shoulder 39 formed in the wall of the cup. The rear end of the cup 37 projects rearwardly through an aperture in the cap 13 and the cap 13 is provided at a point opposite the air inlet 36 with an air vent 40.

A coil spring 41 is positioned within the collar 35 and is compressed between the shoulder 39 on the cup 37 and the rear end 42 of the plug 30. In the rearmost position of the cup 37 the air inlet 36 is uncovered by the rim of the cup and permits air to enter the space enclosed within the cup and collar. As soon as the cup 37 is pressed forwardly, by the application of finger pressure thereto, the air inlet 36 is closed off and the air trapped within the cup and the collar is forced forwardly through the passage 31 in the plug past the ball 32, which ball will thereupon seat and cause the air which has been forced into the inside of the tube 15 to remain therein under pressure.

60 The ink sack 16, which is located within the

tube 15, is of readily collapsible construction, and is preferably made of some very thin limp material which will not offer any appreciable resistance to being progressively collapsed, even under ordinary atmospheric pressure.

The increased pressure on the air surrounding the sack 16 within the tube 15 will therefore tend to collapse the sack and cause the ink, which completely fills the same, to be urged toward the writing ball 22.

Whenever the feed of the ink to the writing ball shows any indication of slowing down in writing it is merely necessary to increase the air pressure within the reservoir by operating the pumping device one or more times.

It will be appreciated that the ink reservoir 14 may be made either as a permanent part of the writing instrument or as a readily replaceable cartridge, with the writing tip either permanently associated with the casing of the writing instrument or the cartridge.

It will of course be understood that the front end of the writing instrument is adapted to be protected, when not in use, by a removable cap (not shown) of any suitable design.

In the modification shown in Fig. 4 the ink, instead of being placed in a collapsible container, is placed in bulk form in the front portion of the tube 43 of the reservoir, completely filling the space in front of a free piston 44. The piston 44 is sealed relative to the inner wall of the tube 43 at both its front and rear ends by cup-packings 45 and 46 which are secured to the piston. The cup-packings 45 and 46 may, if desired, be secured to the piston by a tubular rivet 47, with a plug 48 removably positioned in the rivet. The plug 48 may be removed to facilitate the filling of the tube 43 with ink without entrapment of any air in front of the piston 44.

The writing instrument shown in Fig. 5 is of the capless type, in which the writing tip 49 when not in use is housed in a retracted position within a bore 50 in the front end of the casing 51.

When an exposed operating button 52 on the rear end of the casing 51 is pressed forwardly it acts through a thrust member 53 located on the front end of a latching mechanism 54 to project the ink cartridge 55 forwardly. The cartridge 55, in moving forwardly, carries with it the writing tip 49, against the yielding resistance offered by a compressed coil spring 56.

The particular projecting and retracting mechanism shown is of the type disclosed in my copending application Serial No. 609,277, now Patent #2,483,329 dated September 27, 1949, but may be of any other suitable construction. The first push on the button 52 projects the tip 49 into the exposed position shown in dotted lines and latches the tip in that position. The next push on the button 52 releases the latching mechanism and allows the tip to move rearwardly into its housed position.

The ink cartridge 55 includes a tubular housing 57 and a collapsible sack 58. The sack 58, which is positioned within the housing 57, contains the reserve supply of ink and is connected at its front end with the ink feeding duct leading to the tip 49. The thrust member 53 is provided with a forwardly extending stem 59 on which an air compressing piston 60 is mounted. The piston 60 is located within the housing 57 near the rear end 61 of the latter, opposite a narrow relief groove 62 in the wall of the housing. In its retracted position the housing 57 is held against further rearward movement, in forwardly spaced relation

to the thrust member 53, by abutment with a snap ring 63 set into the wall of the housing.

When the thrust member 53 is moved forwardly by operation of the button 52, the piston 60 slides forwardly within the housing 57 beyond the relief groove 62 and serves to place the air about the sack 58 under pressure. The thrust member 53 then moves into engagement with the rear end 61 of the housing 57 and moves the housing forwardly, thereby projecting the tip 49 into its exposed writing position, with the air in the housing 57 still held under compression by the piston 60.

When the thrust member 53 is thereafter permitted to move rearwardly by a second push on the button 52, the housing 57 will also move rearwardly, the tip 49 will be retracted, and the piston 60 will shift back into a position opposite the relief groove 62, thereby allowing the built-up air pressure on the sack 58 to be released.

I claim:

1. In a writing instrument of the type employing a rotatably mounted ball as the writing tip, which tip is adapted to be protectively enclosed

25 when the instrument is not in use, an ink receptacle which is provided at its front end with an ink feeding duct leading to the ball, means for moving the tip into an exposed writing position, means for creating air pressure on the ink, and exteriorly accessible means for simultaneously operating both of said two last mentioned means.

2. In a writing instrument of the type employing a rotatably mounted ball as the writing tip, a casing, manually operable means for projecting and retracting the writing tip relative to the front end of the casing from a protectively enclosed position to an exposed writing position, an ink receptacle which is movable with the tip and is provided at its front end with an ink feeding duct leading to the tip, means for creating air pressure on the ink, and exteriorly accessible means for simultaneously operating both said tip projecting means and said air pressure creating means.

3. In a writing instrument of the type employing a rotatably mounted ball as the writing tip, a casing, manually operable means for projecting and retracting the writing tip relative to the front end of the casing from a protectively enclosed position to an exposed writing position, an ink receptacle which is movable with the tip and is provided at its front end with an ink feeding duct leading to the tip, means for creating and retaining air pressure on the ink, exteriorly accessible means for simultaneously operating both said tip projecting means and said air pressure creating means, and means operable upon retraction of the tip to relieve said air pressure.

JOHN C. WAHL.
